VISUAL RECORD TALLYING DEVICE

James T. Caradine, St. Louis, Mo.

Application January 16, 1950, Serial No. 138,896

6 Claims. (Cl. 35—24)

1

This invention relates in general to counting devices, and more particularly to certain new and useful improvements in inventory tallying devices, designed to present a visual record.

The primary object of the present invention is to provide a counting device which, in a very simple, economical manner, makes possible the maintenance in offices and business houses of a continuous visible count and record of any desired data in what may be called a "graphic tally" from which one may instantaneously and at a glance derive a conclusion without laborious reference to written record-sheets.

An additional object of the present invention is the provision of a visual-record counting device comprising a case having a plurality of graduated, counter-receiving posts normally concealed within the case to prevent unauthorized tampering and adapted for vertical movement into exposed position for graphically presenting a complete, visible inventory of the stock in trade.

A further object of the present invention is the provision of a visual-record counting device which may be adapted to record inventory data relative to any number of stock items, and which is easily maintained to present a continuing or current inventory, and thereby eliminates the necessity of taking periodic, laborious inventories as is generally customary.

An additional object of the present invention is the provision of an inventory tallying device which is simple in construction, thoroughly reliable and effective for the purposes intended thereof, and economically manufactured.

With the above and other objects in view, my invention resides in the novel features of form, construction, arrangement, and combination of parts presently described and pointed out in the claims.

In the accompanying drawings (two sheets)—

Figure 1 is a perspective view of an inventory tallying device constructed in accordance with and embodying the present invention;

Figure 2 is a transverse sectional view taken along line 2—2 of Figure 1;

Figure 3 is a fragmentary transverse sectional view taken along line 3—3 of Figure 2;

Figure 4 is a fragmentary transverse sectional view taken along line 4—4 of Figure 3;

Figure 5 is a transverse sectional view taken along line 5—5 of Figure 2;

Figure 6 is a fragmentary sectional view showing the counting post board in elevated position;

Figure 7 is a fragmentary sectional view showing the locking pawl in operative position;

2

Figure 8 is a fragmentary sectional view showing the locking pawl in inoperative position;

Figure 9 is a fragmentary transverse sectional view taken along line 9—9 of Figure 5; and

Figure 10 is a perspective view of a counting disc.

Referring now in more detail and by reference characters to the drawings which illustrate a preferred embodiment of the present invention, A designates a counting or tallying device comprising a rectangular case 1 being opened at its top and having side walls 2, 2', and end walls 3, 3', the latter being centrally provided with vertically extending apertures 4, 4', respectively, which are rounded at their upper and lower ends. Disposed in said apertures 4, 4', for free movement therein are collars 5, 5', respectively, mounted upon a transversely extending shaft 6 which projects outwardly at one of its ends beyond the aperture 4 and has mounted upon its outer projecting extremity a handle member 7. Suitably mounted upon said shaft 6, immediately adjacent to, and inwardly of, the collars 5, 5', are spur gears 8, 8', respectively, meshingly engaged with vertically disposed racks 9, 9', respectively, mounted upon the inner faces of the end walls 3, 3', and terminating at their upper ends spacedly from the upper margins thereof, (see Figure 5). The shaft 6 extends through bracket members 10, 10', which are secured to the under face of a rectangular base plate or lift board 11, of slightly decreased lateral dimensions and being disposed in normal relation to the walls 2, 2', 3, 3'. The brackets 10, 10', are of sufficient height to maintain said plate 11 spacedly above the shaft 6, as may be seen in Figure 5.

Mounted centrally upon the inner faces of the side walls 2, 2', are vertically extending racks 12, 12', respectively, with which are meshingly engaged pinions 13, 13', respectively, suitably mounted upon the ends of a rod 14 extending transversely across the under face of the base plate 11, through the space between the shaft 6 and said base plate 11, in normal relation to the shaft 6. Inwardly of, and adjacent to, the pinions 13, 13', said rod 14 extends loosely through brackets 15, 15', secured to the under face of the plate, or so-called "lift board" 11. Thus, it will be seen that upon manual rotation of the handle element 7, the gears 8, 8', will be driven upwardly along their associated racks 9, 9', and thereby elevate the base plate 11, with the collars 5, 5', moving freely within the apertures 4, 4'. Simultaneously, the pinions 13, 13', will be driven upwardly by the racks 12, 12', respectively, and

thereby the base plate 11, will be provided with support adjacent all four of its sides, so that it will be maintained at all times in parallel relation to the horizontal.

On the inner face of the end wall 3, adjacent the upper end of the aperture 4, there is disposed a locking pawl 16 having an outwardly extending handle portion 17, projecting through a suitable aperture in the wall 3, upon manual operation of which the pawl 16 may be swung into locking engagement with the gear 8, as shown in Figure 7 for maintaining the plate 11 in elevated position, or into inoperative position, as shown in Figure 8.

Mounted upon the upper face of the plate 11 and suitably secured thereto, as by rivets 18, is a tallying unit or so-called "counting-post board" 19 of substantially the same dimensions as the plate 11. Said counting-post board 19 is provided in its upper face with a multiplicity of, preferably circular, recesses 20 disposed in transverse and longitudinal alignment, each being adapted for rigidly receiving the lower end of an upstanding post 21 having a flattened face portion 21' with graduated markings 22, of a suitable scale, imprinted or otherwise delineated thereon. Each post 21 is axially aligned with a relatively enlarged circular aperture 23 in a rectangular cover or label board 24 presented across the top of the case 1 disposed in loosely seated disposition upon the upper end faces of the racks 9, 9', 12, 12'. Adjacent the central portions of each side margin of the board 24 is an aperture 25 within which is disposed a pin member 26, beveled at its lower ends for secure retention therein and projecting at its upper end beyond the plane of the board 24. Mounted upon the projecting end of each pin 26 is a locking arm 27 and a knurled knob 28 for rotating said pin 26 in order to swing the arm 27 into or out of locked engagement with a keeper member 29 mounted upon the upper margin of each end wall 2, 2'. Thus, with the locking arms 27 in locked engagement with the keepers 29 the cover or label board 24 is maintained securely in position.

Upstandingly disposed upon the cover board 24 along one side thereof is a legend board 30 suitably provided on its rearwardly presented face with angle cleats 31 for insertion at their lower ends in brackets 32 mounted upon the upper face of the board 24 whereby said panel 30 may be maintained securely in upright position. On its inwardly presented face the legend board 30 is provided with a plurality of spaced indicia members 33, such as glass buttons or jewels, of preferably varying colors, as white, red, blue, green and the like, whereby each color will indicate a certain predetermined number of measuring units. Thus, depending upon the particular scale to be utilized, the white button could indicate ten units or ten dozen, as the case may be, with the red designating twenty units or twenty dozen, and so forth. The particular designation of each member 33 is entirely arbitrary with the user.

There is provided for removable disposition upon the post 21, annular counting or tally discs 34 having a central opening of slightly greater diameter than the posts 21 and an overall diameter slightly less than that of the apertures 23 in the cover board 24. Said discs 34 are fabricated preferably of a conventional thermoplastic and are colored to agree with any one of the indicia members 33. For example, a red disc would

be equivalent to the same number of units, as the red indicia member 33 indicates.

Suitably inscribed upon the cover board 24 adjacent each of the apertures may be a label 35 bearing a code-letter, or number referring to or the precise name of, a particular article of merchandise carried in inventory. Thus, a label 35 may be disposed adjacent one aperture 23 indicating in selected terminology, for example, "Men's shoes, size 9½," and the next adjacent aperture 23 may have a label 35 indicating "Men's shoes, size 10." Therefore, each aperture 23 will relate to one item of merchandise. It is, of course, apparent that the device A may be of any convenient size to accommodate the number of apertures 23 with related posts 21 necessary for the particular operation involved.

In usage, the base plate 11 may be elevated in the manner hereinabove described and locked in such position by operation of the locking pawl 16. In this position the counting posts 21 will project upwardly through their respective apertures 23 in the cover board 24 in completely exposed position, as may be seen in Figure 6. After the amounts of any one particular item of merchandise have been determined, the appropriate discs 34 in requisite number, are disposed upon the post 21 associated with the aperture 23 corresponding to the various items of merchandise. For example, if the number of pairs of shoes of size 9½ is normally carried in an amount of fifty pairs or more, a disc 34 of the appropriate color indicating five pairs could be utilized, and the user would place ten of such discs 34 upon the counting post 21. As stated above, the posts 21 are graduated to a convenient scale, which is designed to indicate rapidly the number of discs 34 which may be disposed thereon. Thus, the graduated markings 22 could be in spaces of 5's so that each space would be equivalent to the height of five of the discs. The user could immediately determine the amount of the particular item of stock by looking at marking 22 nearest the top of the stock of discs 34 upon any post 21. For instance, the marking 22 could be ten and if there were one or two discs 34 above the number ten mark it would easily be determined that there were fifty-five or sixty units, as the case may be.

In the event there was an odd number of units in stock, as for example, fifty-one, the user could put ten of the "five unit" discs 34 and one "one unit" disc 34 upon the appropriate post 21.

After completion of the inventory-taking, with the placement of the requisite discs 34 upon the respective posts 21, there is presented a visual graphic indication of the inventory carried. The locking pawl 16 may then be moved to permit descent of the base plate 11 whereby the posts 21 will then be concealedly disposed within the interior of the case 1. This is a most important feature since it prevents unauthorized inspection of the inventory count. In the normal course of business, as stock is added or taken out, the discs 34 on the posts 21 may be appropriately added or removed in accordance therewith so that a running or current inventory is easily maintained.

If desired, the counting post board 19 and its associated posts 21 may be built separately from the plate 11 and a plurality of such separate units suitably labeled or with label boards 24 and legend boards 30 suitably attached may be supplied for use by executives or for use by executives or for use as a transfer board so that totals

from one or more of the tallying devices A can be accumulated, consolidated, or recapitulated. For example, a so-called transfer board may be made up of a counting post board 19 with a label board 24 and a legend board 30 rigidly attached so as to be used to transfer, at certain closing periods, the count, taken from one or more of the tallying devices A by using higher value counting discs 34, which may be of a different color and may represent some selected multiple of the counting disc 34 used with the tallying device A. Similarly, an executive board may be made by rigidly connecting a counting post board 19 and a label board 24. In this connection, it has been found convenient, in actual practice, to make the executive boards as a reduced, scale replica of the counting post board 19 and label board 24 so that it will be compact enough to set either at the rear or one side of an executive's desk without being too cumbersome so that the needed information is visible for comparison at all times.

A number of these separate transfer and executive boards may be supplied to make up a complete business system so that executives, accountants, and other persons required to use such information may record such items as sales by salesmen, districts, states, expenditures by departments, purchases, income, and the like so that these items of information can be recorded in visual, graphic form, obviating the necessity of preparing and transferring a great multiplicity of figures onto written lists.

It should be understood that changes and modifications in the form, construction, arrangement, and combination of the several parts of the counting device may be made and substituted for those herein shown and described without departing from the nature and principle of my invention.

Having thus described my invention what I claim and desire to secure by Letters Patent is:

1. A visual record counting device comprising a case, a first board disposed across the top of said case and being provided with a multiplicity of apertures, a second board disposed within said case and adapted for vertical movement therein, a plurality of spaced posts disposed upstandingly upon said second board, each post being aligned with an aperture of said first board and being of substantially smaller size than such aperture for extension therethrough when said second board is in upwardly shifted position, and a plurality of washer-like counters having an external size smaller than the apertures of the first board, each washer-like member further being provided with an opening adapted to fit around the post so that the washer-like members may be removably disposed upon said posts and being adapted when so mounted to pass through said apertures with said posts for according a viewable graphic representation of recorded data.

2. A visual record counting device comprising a case being open at its upper and lower ends, a first board removably disposed across the open upper end of said case and having a multiplicity of apertures opening into the interior of said case, a plate disposed within the case in parallel relation to said first board and being adapted for vertical movement, a second board mounted upon the upper face of said plate, upstanding spaced posts normally concealed within the case, mounted at their lower ends in said board, each of said post members being aligned with an aperture in said first board for projection therethrough into

exposed position upon upward movement of said plate member, a plurality of washer-like counters having an external size smaller than the apertures of the first board, each washer-like member further being provided with an opening adapted to fit around the post so that the washer-like members may be removably disposed upon said posts and being adapted when so mounted to pass through said apertures with said posts for affording a viewable graphic representation of recorded data, and means for locking said plate in its upward shifted position to maintain said post members in exposed position.

3. A visual record counting device comprising a case, being open at its top and bottom ends, a first board removably disposed across the open top end of said case and having a multiplicity of apertures opening into the interior of the case, each of said apertures having associated therewith a label, a plate disposed within said case in parallel spaced relation to said first board, gear means associated with said plate whereby said plate may be raised and lowered within said case, a second board mounted upon the upper face of said plate in parallel relation to said first board, upstanding post members mounted at their lower ends in said second board and being normally concealed within said case when said plate is in lowered position, each of said post members being aligned with an aperture in said first board whereby upon upward shifting movement of said plate said post members will project through said apertures into completely exposed position, a plurality of washer-like counters provided for removable disposition upon said post members for affording a viewable graphic representation of recorded data, and locking means for optionally maintaining said plate in upward shifted position.

4. In a visual record counting device for the presentation of quantitative data in visual graphic form, the combination of a case, a first board removably disposed across the upper end of said case and having a multiplicity of apertures opening into the interior of said case, each aperture having associated therewith a label, a legend board disposed upstandingly upon the upper face of said first board and having a plurality of indicia members, a second board disposed within said case and adapted for vertical shiftable movement, upstanding post members mounted at their lower ends in said second board and having graduated designations throughout their length, each of said posts being aligned with an aperture in said first board whereby upon upward movement of said second board said post members will project through said apertures into completely exposed position, and counting members corresponding with the indicia members on said legend board for disposition upon said posts to indicate the number of units in inventory of the item being tallied on each post member.

5. A visual record counting device comprising a case, a board disposed in said case and being adapted for vertical movement within said case, upstanding flat-sided post members disposed at their lower ends in said board, a cover board member disposed across the top of said case and having a multiplicity of apertures opening into the interior of said case, each of said apertures having associated therewith a designating label and being aligned with a post so that the post will extend therethrough when the second board is in upwardly shifted position, and a plurality of washer-like counters provided for removable dis-

position upon said post members and having a circular aperture for loosely embracing the post whereby to afford a viewable graphic representation of recorded data, the apertures in said cover board being substantially larger in diametral size than the diametral size of the posts and washers combined so that when the washers are mounted upon the posts they will freely clear the apertures in the cover board when the post carrying board is in elevated position.

6. A visual record counting device comprising a case being open at its top and bottom ends, a first board removably disposed across the open top end of said case and having a multiplicity of apertures opening into the interior of the case, each of said apertures having associated therewith a label, a plate disposed within said case in parallel spaced relation to said first board, means operatively associated with said plate whereby said plate may be raised and lowered within said case, a second board mounted upon the upper face of said plate in parallel relation to said first board, upstanding post members mounted at their lower ends in said second board and being normally concealed within said case

5 when said plate is in lowered position, each of said post members being aligned with an aperture in said first board whereby upon upward shifting movement of said plate said post members will project through said apertures into completely exposed position, a plurality of washer-like counters provided for removable disposition upon said post members and affording a viewable graphic representation of recorded data, and locking means for optionally maintaining said plate in upward shifted position.
